CLAIM

The ornamental design for a wireless diffuse infrared LAN transceiver, as shown and described.

DESCRIPTION

FIG. 1 is a perspective view of the wireless diffuse infrared LAN transceiver, the broken line showing of a personal digital computer is for illustrative purposes only and forms no part of the claimed design;

FIG. 2 is a front elevational view of the wireless diffuse infrared LAN transceiver of FIG. 1;

FIG. 3 is the rear elevational view of the wireless diffuse infrared LAN transceiver of FIG. 1;

FIG. 4 is the left elevational view of the wireless diffuse infrared LAN transceiver of FIG. 1;

FIG. 5 is the top plan view of the wireless diffuse infrared LAN transceiver of FIG. 1;

FIG. 6 is the right elevational view of the wireless diffuse infrared LAN transceiver of FIG. 1; and,

FIG. 7 is the bottom plan view of the wireless diffuse infrared LAN transceiver of FIG. 1.
